(57) **CLAIM**

The ornamental design for a toy vehicle, as shown and described.

DESCRIPTION

FIG. 1 is a top front perspective view of a toy vehicle showing the new design;

FIG. 2 is an enlarged front side elevational view of the toy vehicle of FIG. 1;

FIG. 3 is an enlarged rear side elevational view of the toy vehicle of FIG. 1;

FIG. 4 is a right side elevational view of the toy vehicle of FIG. 1;

FIG. 5 is a left side elevational view of the toy vehicle of FIG. 1;

FIG. 6 is a top plan view of the toy vehicle of FIG. 1; and,

FIG. 7 is a bottom plan view of the toy vehicle of FIG. 1. The broken lines and unshaded areas form no part of the claimed design.
